UNITED STATES PATENT OFFICE.

BERTROM ANDERSEN, OF KANSAS CITY, KANSAS.

VAPOR-BATH APPARATUS.

No. 927,629.

Specification of Letters Patent.

Patented July 13, 1909.

Application filed May 29, 1908. Serial No. 435,678.

To all whom it may concern:

Be it known that I, BERTROM ANDERSEN, a subject of the King of Denmark, residing at Kansas City, in the county of Wyandotte 5 and State of Kansas, have invented certain new and useful Improvements in Vapor-Bath Apparatus, of which the following is a specification.

This invention relates to vapor bath apparatus and more especially to apparatus enabling a person to take a bath in the steam arising from an ordinary bath tub and my object is to produce apparatus which can be easily, quickly and conveniently placed in or 15 removed from operative position upon a bath-tub.

A further object is to produce an efficient and reliable apparatus of this character embodying the desirable features of simplicity, 20 strength, durability and cheapness of construction.

To these ends the invention consists in certain novel and peculiar features of construction and organization as hereinafter described and claimed; and in order that it 25 may be fully understood reference is to be had to the accompanying drawing, in which—

Figure 1, is a vertical central longitudinal 30 section of an apparatus embodying my invention and a part of a bath tub supporting the same, the position of the bather being indicated by dotted lines. Fig. 2, is a fragmentary plan view of the chair portion of the apparatus. Fig. 3, is a section on the line 35 III—III of Fig. 1. Fig. 4, is an enlarged vertical section taken on the dotted line IV—IV of Fig. 2. Fig. 5, is a section on the line V—V of Fig. 4.

40 In the said drawing, a seat-frame is constructed as follows:

1 and 2 indicate a pair of cross bars of sufficient length to bridge a bath-tub A and provided in their under sides with recesses 3 to 45 fit snugly upon the external roll portion or flange B of the bath-tub to prevent any possibility of lateral slippage.

4 indicates longitudinal bars connecting bars 1 and 2, and 5 is a cane seat or bottom 50 for the frame, it being understood of course that any suitable seat, preferably a foraminous one, may be employed.

6 indicates a hinged back for the seat, the same consisting preferably of a rectangular 55 frame bridged or covered by a cane or equivalent back 7, and hinged as at 8, to the seat-

frame in order that the angular relation between the seat-frame and back may be varied.

9 indicates braces pivoted as at 10^a, to the 60 sides of the back 6 and extending downwardly and forwardly therefrom and fitting in recesses or grooves 10 in the cross bar 2.

11 indicates a longitudinal series of sockets 65 or grooves in the under sides of braces 9, and 12 are plates secured to the undersides of said braces and provided with openings 13 corresponding in width to the sockets but of shorter length by preference as shown most clearly in Fig. 4.

14 are screws secured in cross bar 2, in the 70 plane of grooves 10 thereof, having their heads disposed above the bases of said grooves a distance slightly exceeding the thickness of plates 12, the heads of the 75 screws being adapted to enter the openings or sockets 11, and overlap plate 12 at the front ends of openings 13 thereof in order to secure the hinged back at the desired angle.

In the drawing the head of the screw 80 shown is flattened as at 15, to enter either of the sockets of the narrow thin brace 9, but this flattening of the screw heads is a matter of no importance as it simply involves the 85 question of proportion.

16 indicates hangers consisting of a pair of bars depending from the sides of the seat-frame and provided with vertical series of holes to receive the bolts 17. An adjustable frame consists of a pair of side bars 18 extending through the space between bars of the hangers, and resting on vertically adjustable bolts 17 and the cross bar 19 at the foot ends of bars 18, the latter being hinged 90 at their opposite ends at 20 to the side bars 95 of the seat-frame. Hinged as at 21 to the side bars 18 is a foot-rest consisting of a pair of side bars 22 connected by cross sills 23 and hinged to and extending downward and forward from said foot-rest is a notched 100 brace 24 for engagement with cross bar 19, the upper edge of said bar 19 being notched at 19^a to receive the brace 24 and prevent lateral slippage or movement thereof, it being obvious that by a proper adjustment of 105 the brace the foot rest can be disposed at varying angles to the seat.

25 indicates a curtain or cover, preferably of waterproof material and adapted to be draped completely over the chair and the 110 upper part of the supporting bath-tub, the said curtain being preferably provided near

its lower margin with a drawstring 26 to permit the curtain to be drawn tightly around the body of the tub below the roll or flange B thereof. The curtain is provided 5 with an opening 27 through which the occupant's head is adapted to project and then the curtain is drawn snugly around the neck of the occupant so as to prevent the escape of steam through said opening, and for the 10 comfort of the occupant, said curtain is adapted to be equipped at the rear side of said opening with a cushion or head-rest 28 which will bear against the upper end of the hinged back of the chair.

15 In practice the apparatus is first arranged in proper position upon the bath-tub with the curtain draped loosely around the latter, the person who is to take a vapor bath then raises the curtain at one side and seats him- 20 self upon the chair, the brace 9 at the corresponding side being first raised out of the way if desired to permit such position to be assumed by the occupant with greater ease and convenience, the said brace being then 25 resecured in position. An attendant then operates the draw-string to secure the curtain around the tub. The faucet, not shown is then opened to charge the tube with the desired quantity of hot water, from which 30 the steam will arise and envelop the occupant of the chair. It will thus be seen that a person can take a steam vapor bath with his head completely uncovered and thus avoid danger of inhaling the steam or having 35 his hair unnecessarily dampened.

From the above description it will be apparent that I have produced a vapor bath apparatus possessing the features of advantage enumerated as desirable and I wish it 40 to be understood that I do not desire to be restricted to the exact details of construc-

tion shown and described, as obvious modifications will suggest themselves to one skilled in the art.

Having thus described the invention what I claim as new and desire to secure by Letters-Patent, is:—

1. A vapor bath apparatus comprising a seat adapted to engage the edge of a bath tub and be supported thereby, a back hinged 50 to the seat and extending upward therefrom, braces hinged at their upper rear ends to the back and having their lower front ends adjustably engaging the front edge of the seat, hangers depending within the tub 55 from the seat near the front edge of the same, a frame hinged at its rear end to the under side of the seat near the rear edge thereof and adjustably supported near its front end by said depending hangers, and a foot rest 60 carried by the front end of said frame.

2. A vapor bath apparatus comprising a seat adapted to engage and be held by the edge of a bath tub, a back hinged to the seat and extending upward therefrom, braces 65 hinged at their upper rear ends to the back near the upper end of the same and provided in their under sides with longitudinal series of sockets, plates on the under sides of the braces having openings registering with but 70 of less area than the said sockets, headed retainers secured in the seat and having their heads entering the sockets and engaging the said plates, a frame adjustably supported on the under side of the seat, and a foot rest 75 carried by the front end of said frame.

In testimony whereof I affix my signature, in the presence of two witnesses.

BERTROM ANDERSEN.
